his Attorneys.

UNITED STATES PATENT OFFICE.

JOHN H. ANGEL, OF MINNEAPOLIS, MINNESOTA.

PRESS-PLATE.

1,349,544.

Specification of Letters Patent. Patented Aug. 10, 1920.

Application filed May 16, 1919. Serial No. 297,628.

To all whom it may concern:

Be it known that I, JOHN H. ANGEL, a citizen of the United States, residing at Minneapolis, in the county of Hennepin and 5 State of Minnesota, have invented certain new and useful Improvements in Press-Plates, of which the following is a specification.

My invention relates to press plates for 10 expressing presses and an object is to provide press plates which will prevent oil meal cakes from spreading and which will cause the oil to be expressed in a thorough manner.

The full objects and advantages of my in- 15 vention will appear in connection with the detailed description thereof and the novel features embodied in my inventive idea will be particularly pointed out in the claims.

Referring to the drawings,— 20 Figure 1 is a side view, partly in section, of a press. Fig. 2 is a top plan view of my press plate. Fig. 3 is a view in vertical section of a portion of two press plates in co-operative relation. Fig. 4 is a view in vertical section at right angles to Fig. 3.

As shown in the drawings, 10 designates the plunger of a hydraulic press of any well known form, the press being provided with four corner posts 12 and having a top member 14. A plurality of press plates 16 are employed in the press, these plates being connected in such manner that they are capable of movement toward each other when the plunger is applied, while they have a 30 limited movement from each other when the pressure is relieved. To provide for this operation opposite sides of the plates are provided with bolts 18, the bolts of adjacent plates being connected by links 20 held thereon for sliding movement by the 40 heads of the bolts. The bolts and links of successive plates are arranged in staggered relation, as shown in Fig. 1, so as to permit sliding movement of the links. The opposite 45 sides of the plates are also provided with notches 22 in which the inner surface of the posts 12 engage to retain the plates in proper position for sliding movement, and the upper press plate is secured to the top 50 member 14. The opposite faces of the plates 16 are provided with pressing surfaces and these pressing surfaces are preferably formed in separate members 24 secured upon the opposite faces of the plates 16 by rivets 26. The marginal portions of the members 24 are thicker than the middle por-

tions thereof, and these marginal portions are beveled, as shown at 28. The surfaces of the members 24 which lie within the beveled margins are provided with transverse corrugations 30 and from the depressed portions of the corrugations, grooves 32 extend through the beveled margins so as to permit oil to flow into gutters 34 at the sides of the press plates in the upper surfaces thereof. The gutters 34 at one end are connected by a cross gutter 36 and the gutters 34 at the other end are open so that the oil can drain off into troughs in the usual way.

In operation oil meal cakes 38, from which the oil is to be expressed, are provided on their tops and bottoms with press cloths 40 and the cakes are introduced between successive press plates while the plunger of the 75 press is retracted. Upon applying pressure by means of the plunger, the oil is squeezed out of the cakes and escapes through the grooves 32 into the gutters 34 at the sides. The oil which escapes at the end which is 80 provided with the gutters 36 runs into the gutters 34 and the oil which escapes at the other end drains directly into the troughs which have been referred to. The beveled margins and corrugations of the press plates 85 prevent the cakes from spreading beyond the limits of the press plates and cause the oil to be expressed more thoroughly. The effect of the beveled margins is to force the material, of which the cakes is composed, inwardly, 90 and a more efficient squeezing action is attained by means of the corrugations. When the pressing of the cakes has been completed, the plunger is retracted and the press plates 95 gravitate from each other by a movement limited by the links 20. The cakes which have been pressed are then removed, the press cloths preventing the material from adhering to the plates.

I claim:

1. A press plate for expressing presses having its opposite faces provided with corrugations and its upper face outside of the corrugations provided with gutters connected by grooves with the depressions of 105 the corrugations.

2. A press plate for expressing presses having its opposite faces provided with transverse corrugations and its upper face outside of the corrugations provided with 110 longitudinal gutters connected by grooves with the depressions of the corrugations.

100

3. A press plate for expressing presses having its opposite faces provided with pressing surfaces, the margins of which are beveled so as to leave the periphery of 5 greater thickness than the rest of the pressing surface, and transverse corrugations formed in the pressing surfaces lying within said beveled margins and having the upper

surface outside of the pressing surface provided with longitudinal gutters connected 10 with the depressions of the corrugations by grooves extending through said beveled margins.

In testimony whereof I hereunto affix my signature.

JOHN H. ANGEL.
